CLAIM

The ornamental design for money clip with RFID payment device and optional biometric activator, as shown and described.

DESCRIPTION

FIG. 1 is a front view of the money clip with RFID payment device and optional biometric activator;

FIG. 2 is a perspective view of the money clip with RFID payment device and optional biometric activator;

FIG. 3 is a cross-sectional taken along the lines of 3—3 in FIG. 1; and,

FIG. 4 is a perspective view of the money clip with RFID payment device and optional biometric activator in exemplary use.

It being understood that the broken lines in FIG. 4 are for illustrative purposes only and form no part of the claimed design.
